UNITED STATES PATENT OFFICE.

GEORGE C. CLARK, OF EVERETT, WASHINGTON.

VACUUM-FEED FOR OIL-ENGINES.

1,309,718.

Specification of Letters Patent. Patented July 15, 1919.

Application filed March 3, 1919. Serial No. 280,464.

To all whom it may concern:

Be it known that I, GEORGE C. CLARK, a citizen of the United States, and resident of the city of Everett, county of Snohomish, 5 and State of Washington, have invented certain new and useful Improvements in Vacuum-Feeds for Oil-Engines, of which the following is a specification.

My invention relates to vacuum feed devices of the sort that are used for supplying gasolene to the engines of automobiles.

The object of my invention is to provide a device of this character, which will be simple in its construction, thoroughly reliable 15 in its action, and which will avoid certain objections to the device which has been in common use up to the present time.

The particular features of which this invention consists, will be seen from a study 20 of the specification and the claims, in which latter the particular points of novelty upon which patent is desired have been pointed out.

In the accompanying drawings I have 25 shown my invention in the form which I now prefer to make the same.

Figure 1 is a vertical section on a central plane of my invention.

Fig. 2 is a similar view, showing the parts 30 in different positions.

Figs. 3 and 4 are horizontal sections taken through the suction pipe and through the suction controlling valve.

Fig. 5 is a vertical section through the 35 boss containing the valves and the ports.

Fig. 6 is a section taken through the top of the oil inlet chamber, showing the manner of mounting the valve-operating lever.

This invention relates to the type of 40 mechanism for supplying oil to an oil engine which is generally referred to as the vacuum feed system. Broadly speaking, it consists in employing an oil inlet or suction chamber and an oil discharge or feed chamber, the two being mounted at such a level 45 that the oil will flow by gravity from the feed chamber to the carburetor of the engine and also at a level which is above that of the main storage tank. The force used for 50 drawing the oil from the storage tank to the vacuum feed device is the partial vacuum which is produced by the engine cylinders when drawing in the charge.

One of the objects of my invention has 55 been to provide a device which has no balanced or neutral position, but which will

work positively, even if the device is mounted upon a support which is stationary.

In the drawings, 1 represents the exterior tank, this functioning as the oil delivery or 60 feed tank, from which the oil is taken direct to the carburetor of the engine. Within this is the oil inlet or suction tank 2. The latter is of smaller capacity than the former, and for convenience, has been placed within 65 and at the upper part of the former. This arrangement is a convenient and desirable one, but is not essential for the correct operation of the device.

The oil inlet or suction tank, 2, has an inlet or supply pipe 3 which leads to the main storage tank. This inlet pipe 3 is herein shown as extending downward through the delivery chamber 1 and as also serving as the tubular seat for a cylindrical valve 4 by 70 which the flow of oil to each of the tanks is controlled. It is also provided with a check valve 30, which prevents back flow of oil to the main storage reservoir. The delivery tank 1 is provided with a pipe 31 leading to 75 the carburetor.

The upper end of the inlet pipe 3 is provided, at a point preferably just below the bottom of the inner tank 2, with valve ports 32, through which the oil enters this delivery 80 tank 1. The valve 4, as herein shown, consists of a short section of a tube. This is connected with a tube 40 of a smaller diameter which extends upward through the receiving or inlet tank 2, which tube is provided with ports 41 through which oil is discharged into the inlet or receiving tank 2. 85

It is evident that, by a suitable movement of this valve, the oil may be drawn through the tube 3 and discharged into the inlet or 90 suction tank 2, or discharged from the suction tank 2 into the delivery tank 1.

In the position shown in Fig. 1, if suction be applied to the tank 2, oil will be drawn into this tank. In the position shown in 100 Fig. 2, with the suction removed from the tank 2 oil will be discharged from this tank into the lower tank 1.

The valve 4 is connected with a pipe operated by a piston 5 which is mounted with- 105 in a cylinder 50. As herein shown, this connection is a direct one. The piston rod 51 extends down into the upper end of the receiving or suction chamber 2, and is connected with the upper end of the tube 40. 110 It may be desirable, for many reasons, that this connection be of such character that

slight inaccuracies in the relative placing of the valve rod and the piston rod may be accommodated. I have shown such connection as by a pin 54. This piston is thus connected with the valve so as to move the same.

The power for operating this piston is obtained by connecting the same, as through a pipe 52, with the suction manifold of the engine, or in any other suitable way, so that the suction effect produced by the engine cylinders may be exerted upon the piston 5. The pipe 52 connects with a port 55 formed within the boss 58, in which boss is formed the cylinder chamber 50. Within this boss is also formed a bore 6 in which is mounted a piston valve 60.

This valve has two heads connected by a stem or section of reduced diameter. The central portion of the bore containing this valve is connected by means of a port 56 with the suction port 55. The pipe 52 is at all times connected with the engine so that the suction acts thereon whenever the engine is running.

Ports 61 and 62 communicate with the bore containing the valve 60; toward the ends thereof, their location being such that the movement of the valve will alternately establish communication between the ports 61 and 62 and between the suction port 55, and with the outer air. The ends of the valve receiving bore are at all times in free communication with the exterior air, and in consequence, the movement of the valve alternately forms a connection with the suction and with the outer air.

One of these ports, as 61, communicates with the lower portion of the cylinder bore 50 and the other port 62 communicates with the upper portion. Preferably these are connected with the bore of the cylinder a short distance from the end thereof so as to provide a certain amount of cushioning action for the reciprocation of the piston.

It is evident that the piston 5 is thus enabled to act as a positive force to shift the valve 4. There is, however, no direct connection between the float 7, which is mounted in the suction or receiving chamber, and the valve 4. In other words, the movement of the valve 4 is not caused by the weight or the lifting capacity of the float, but solely by the power of the suction applied through the action of the piston 5.

The float 7, which is contained in the suction chamber 2, is adapted to engage with flanges 70 upon the upper and lower ends of a sleeve 71, which sleeve is mounted to loosely slide upon the tube or stem 40 which connects the valve 4 with the piston 5. This relation of the float and its guide with the valve stem is merely one of convenience and not because of any necessary physical connection between the two. It is done simply as a convenient means of guiding the float.

The upper end of the tube 71, which forms a guide for the float 7, is connected with an arm 72, which is shown as formed of two parts telescoping one within the other in order to accommodate the change in length which is produced by the swinging of this arm. This arm is secured to a shaft 73 which extends through the side wall of a recess 21, which is formed in the cap 20 of the suction chamber 2.

Within this recess 21 an arm 74 is secured to the shaft 73, and to this arm is connected a rod 63 which is connected with the valve 60. The valve 60, which is the suction controlling valve, is a small valve so which may be very easily moved, as it is a piston valve and balanced. The float 7, therefore, has very little work to do to shift this valve and when the valve has been shifted so as to change the application of the suction upon the piston 5, the piston will act promptly to shift the oil controlling valve 4. There will, therefore, be no point at which anything approaching the nature of a dead center will occur. Also, the float, being relieved of the greater work of shifting the oil controlling valve, may be more thoroughly relied upon for doing the small amount of work required of it.

To assist in the prompt action of the valve 60 when being shifted and to hold the same positively in each of its adjusted positions until properly acted upon by the float, I have provided a roller 75, carried by the outer end of the arm 74, and a spring bar 76, which has a projection 77 located so as to engage the roller 75 when in each of its positions, but respectively by opposite sides thereof. This projection is in the nature of a cam.

As the arm 74 is moved to shift the valve it will offer a certain amount of resistance to the movement of the float but when the action of the float has become sufficient to overcome this resistance, it will displace the spring arm until it passes the point of this cam. At this point the float is relieved of the necessity for the extra effort and, in addition, the spring acts to assist the float in moving the valve. In consequence, the movement of the valve will be a sharper movement just at the time when it is shifting from one position to the other. While the use of a spring of this sort will possibly be found desirable, I do not consider that it is really necessary as it will be found that the float will probably shift the small valve even without any assistance from such a spring.

The boss 58, in which the cylinder 50 is formed, has a port 8 formed therein which, at its upper end, communicates with the bore in which the piston rod 51 is placed and at its lower end communicates with the suction chamber.

A port 80 extends horizontally from the exterior of the boss 53 to an intersection with the bore which contains the piston rod 51 and has a continuation at the opposite 5 side continuing as the port 81 to the suction chamber. This port is manifestly neutralized or blocked when the piston rod is in proper position. The piston rod, however, has a groove 42 formed therein in position to 10 match with the ports 80 and 81, and with the port 8 and the main suction port 55.

In the position of the piston shown in Fig. 5, the groove 42 establishes communication between the port 8 and the suction port 55. 15 In consequence, the suction acts upon the chamber 2 and serves to reduce the pressure therein so that oil from the main storage tank will be drawn through the tube 3 into said suction chamber 2. While this is being 20 done the valve 4 is in the position shown in Fig. 1, the piston being up. In this position also the suction is connected with the upper end of the cylinder 50 through the port 62, while the port 61, which connects 25 with the lower end of the cylinder, is in free communication with the outer air. At this time the small float controlled valve 60, which I have called the controlling valve, is in the position indicated in Fig. 3. 30 In this position of the parts the suction will cause a flow of oil into the upper chamber 2. This will cause the float 7 to rise until it contacts with the upper flange 70 of the guiding sleeve 71. It will then raise this 35 sleeve, which causes the arm 72 to swing. This shifts the valve 60 until it reaches the position shown in Fig. 4, in which position the port 62 is in free communication with the outer air and the port 61 is connected 40 with the suction. This will admit atmospheric air to the upper end of the cylinder 50 and exhaust the air from the lower end thereof, thus causing the piston to be drawn downward.

45 This shifts the valve 4 into the position shown in Fig. 2, in which the ports 32 have been opened and the oil is free to flow through the annular chamber 44 and the ports 32, into the lower chamber 1. As this 50 proceeds the float 7 will eventually strike the lower of the flanges 70 of the sleeve 71 and will, through its connection with the lever 72, shift the valve 60 into the other position, or that shown in Fig. 3, whereupon the connection of the atmospheric air and the suction with the cylinder 50 is reversed, causing the piston 5 to be drawn upward.

By this device reliance is not placed upon the power exerted directly upon the float in 60 order to remove the valve, but the float is only called upon to remove a small valve which is balanced and moves very easily, and this valve controls the application of the suction power to a piston which may be 65 made of such size as to be capable of moving

the oil controlling valve even if this should have considerable resistance.

The reliability and operation of the device is thus materially increased. The reliability of the device is also increased by reason of 70 the fact that the valves employed are of a positive type which are not lifted from their seat and, in consequence, their operation is not likely to be disturbed by foreign matter which may get into the oil. 75

What I claim as my invention is:

1. A vacuum feed device comprising an upper intake or suction chamber and a lower feed chamber having a transfer port connecting them, a valve controlling said transfer port, a cylinder and a piston therein connected to actuate said transfer valve, a float in the intake chamber and means controlled by said float and operated independently of said piston to apply air pressure to said piston to thereby operate the transfer valve. 80

2. A vacuum feed device comprising an upper intake or suction chamber and a lower feed chamber having a transfer port connecting them and a transfer valve controlling said port, a cylinder and a piston therein connected to actuate said transfer valve, a valve controlling the application of the engine suction to the cylinder, a float in the 90 intake chamber and means for operating the suction valve by said float. 95

3. A device as in claim 2, having a port for connecting the interior of the intake chamber with the outside air and controlled 100 by said piston.

4. A device as in claim 2 having a port connecting the intake chamber with the suction pipe and intercepted by the piston rod, said rod having a port formed thereon 105 adapted to connect the two parts of the other port.

5. A device as in claim 2 having two ports communicating by one end with the interior of the intake chamber and both intercepted by the piston rod, one of said ports communicating by its other end with the outside air and the other with the suction port, the piston rod having a port therein adapted in different positions to connect the 110 two parts of each of said other two ports. 115

6. A vacuum liquid feeding device comprising an upper intake or suction chamber and a lower feed chamber, a supply pipe extending upwardly through the lower chamber to a connection with the upper chamber and having ports communicating with the lower chamber, a check valve preventing back flow in said supply pipe, a tubular valve slidable in said pipe and controlling 120 its ports, a cylinder having a piston therein, means connecting said piston with the valve in the supply pipe, a valve controlling the application of the suction to the said cylinder, a float within the intake or suction 125 130

chamber, and means whereby the float may shift said suction controlling valve at the top and bottom of the movement of said float.

5 7. A device as in claim 6, having a sleeve loosely surrounding the means which connects the piston and the transfer valve, the float loosely surrounding said sleeve; said sleeve having stops at top and bottom en-

gaging the float, a shaft passing through 10 the top of the intake chamber, an arm carried by the outer end of said shaft and connected with the suction controlling valve, and an arm connected with the inner end of said shaft and connected with said sleeve. 15

Signed at Seattle, Washington, this 24th day of February, 1919.

GEORGE C. CLARK.
